UNITED STATES PATENT OFFICE.

DAVID B. SANFORD, OF WATERTOWN, NEW YORK.

HANDLE FOR BOTTLE-STOPPERS.

No. 875,956.

Specification of Letters Patent.

Patented Jan. 7, 1908.

Application filed September 3, 1907. Serial No. 391,051.

To all whom it may concern:

Be it known that I, DAVID B. SANFORD, a citizen of the United States, residing at Watertown, in the county of Jefferson and State of New York, have invented certain new and useful Improvements in Handles for Bottle-Stoppers, of which the following is a specification.

This invention relates to improvements in handles, designed for application to certain forms of bottle stoppers, and the invention relates particularly to a metallic handle or hand-grip, for use in connection with the paper stoppers or covers employed to close the mouths of milk or like bottles.

The object of the invention is to provide a simple, light, durable and inexpensive handle attachment for milk bottle covers or stoppers, by the use of which, the comparatively light paper disks which are commonly applied to milk bottles by expanding them into the mouths of the bottles, may be inserted and removed repeatedly without mutilating or destroying the said covers, and by the use of which, a bottle may be closed up tightly again and stored away till another supply of milk is required.

The invention consists principally of a piece of tin or other cheap flexible metal having a body of suitable size to permit of being grasped with the thumb and finger of one's hand, and affording a sufficient purchase to enable a person to insert and withdraw the stopper or cover without damaging it.

The invention further consists in forming on the lower or inner end of the piece of metal comprising the handle, two or more binding points or tongues, which are employed for securing the handle to the paper or card-board cover by forcing the points through the web of the disk, and then bending over and clenching the points against the underside of the cover.

The invention further consists in providing means to coöperate with the binding points for holding the body of the handle at right-angles to the outer face of the stopper, so that when the binding points are driven through the paper disks and clenched, a foot-like portion of the handle bears tightly against the upper or outer face of the disk and assists in maintaining the hand-grip in true upright position.

Other features and parts of the invention will be understood from the detail descrip-

tion which follows, and by reference to the accompanying drawing, which forms a part of this specification, and in which—

Figure 1 is a sectional view of the mouth and neck of a bottle with stopper attached, having my improved handle applied. Fig. 2 is a plan and edge view of the handle when first stamped out. Fig. 3 is a compound view, showing the handle bent, being the first operation after the stamping out. Fig. 4 is a plan and edge view, showing handle bent or formed ready for applying to the cover or stopper of a bottle. Fig. 5 is a sectional view of a portion of a bottle with stopper, showing a modified form of handle applied to the stopper. Fig. 6 is a perspective view, showing construction of modified form of handle illustrated in Fig. 5.

Similar characters of reference are given to corresponding parts throughout the several views.

In the drawing, 2 represents the upper portion of a milk bottle, having a mouth 3, in which is formed an annular shouldered recess or depression 4, into which a paper or other like stopper or cover 5 is adapted to fit, for the purpose of tightly closing or sealing the mouth of the bottle, to prevent the escape of milk or other liquid or solid contents.

Milk supplied for domestic use, especially in the cities, is mostly delivered in bottles of different sizes, but practically of the same shape or form. The milk is placed in the bottles by the dealers and for sanitary reasons, they are required to close the mouths of the receptacles with a covering or stopper, which may only be used by the dealer once, and for the purpose of providing an inexpensive, and at the same time a safe and clean stopper for the bottles, a heavy grade of manila or card-board or paper has been adopted and used. These paper stoppers for convenience in their manufacture and use, are made in the form of disks, which may be pressed or expanded into the mouths of the bottles until they bear against the shoulder 4 referred to, and when so placed, they are from a quarter to three-eights of an inch below the top of the bottle. Being flat and circular and disposed some depth into the neck of the bottle, heretofore, there has been no means provided for removing them, after they are once pressed into place, without employing some sharp instrument like a knife or fork to pierce them and thus

afford a means for prying or lifting them out. This mode of removing the covers, often results in tearing or mutilating them, to such extent that they cannot be replaced, or if 5 they are reinserted in the mouths of the bottles, they fail to close them up tightly. Most patrons receiving their milk in bottles prefer to keep the unused milk in the bottles, and in order to enable them to remove the paper 10 covers and insert them in the bottles as often as desired during the day, and at the same time preserve the covers in the same condition they were when first applied to the bottles, I have provided a simple handle 6, 15 preferably made in the form shown in Figs. 1, 2, 3 and 4 of the drawing, which consists of a small piece of stiff tin or other like light cheap and flexible metal, of suitable gage to stand the strain of a handle of the class. 20 This handle is comprised of the body portion 7, which should be of sufficient length and width to afford a grip with the thumb and one finger of a person's hand.

The body portion may be perforated as 25 shown in Fig. 6, for the purpose of aiding the fingers to cling to it while manipulating the cover.

The handle is provided at its lower end with two or more integral binding points or 30 tongues 8, which are preferably formed V-shaped, so that they may be driven through the paper covers or stoppers and then clenched on the underside to hold the handle in rigid position. These binding points are pref- 35 erably bent in the same direction, as shown in Fig. 1, so as to prevent the handle from tilting or becoming loose when applying or removing the stopper. The points 8 may be bent in opposite directions, as shown in Fig. 40 5, if desired, and still provide a strong fastening. The body of the handle near the middle is formed into a compound angle at 9, as shown in Fig. 4, and when applied to the stopper and the points 8 are bent and 45 clenched, this angular portion rests upon the upper face of the stopper in the form of a foot, as shown in Fig. 1. Under this construction the body portion or finger-grip 7 is disposed and rigidly held in a true vertical 50 position, at right-angles to the plane of the stopper, and by reason of the angular part 9, considerable strain may be applied to the handle without disturbing its fastenings.

In Figs. 5 and 6, I have shown a modified 55 form of handle, which in addition to the two binding points 8, is provided with two or more tongues or parts 10, preferably formed with the body of the handle and unpointed. These tongues or feet 10 are bent in opposite 60 directions and at right-angles to the body 7 in such manner, that when the binding points 8 are driven through the paper disks and clenched, they bear against the outer or upper surface of the cover, as shown in 65 Figs. 5 and 6. These tongues or feet are

intended to serve as braces for supporting the body of the handle in true upright position, the same as the angular part 9 in Figs. 1 and 4. Under this construction, the handle is made rigid on the cover, and when, the 70 binding-points are clenched in proper manner, the handle will stand considerable straining before it will become loosened or become detached from the cover. The binding-points are preferably made V-shaped their whole 75 length, so that when they are driven through the card-board, they will at all times tightly fit the slot or kerf and when clenched there will be no opening left for the admission of air into the bottle to change the condition of 80 the milk.

When my improved handles are applied in the manner as described, it is possible for a person to insert and remove the covers of milk bottles an indefinite number of times, 85 without tearing or marring the same, and the covers may be removed and restored in place in a second's time.

My handles are light and inexpensive, and if made of common tinned metal, they will 90 not rust or tarnish during the short interval in which they are used. They are intended to be so cheaply supplied, that they may be thrown away after being used for a day with a bottle of milk.

It is obvious that some changes or modifications may be made in the parts of my handles, without departing from the spirit of the invention, and I therefore do not restrict myself to the precise construction and arrangement of the same as herein shown and described.

Having thus described my invention, what I claim as new and desire to secure by Letters Patent, is—

1. A handle for bottle stoppers, comprising a single piece of sheet metal having a body portion and a pair of binding-points formed on one end thereof, the said body portion being bent near its middle at right angles 110 to form a foot adapted when the binding-points are clenched to rest upon the upper side of a bottle stopper, for the purpose of holding the said handle in true vertical position at right-angles to the plane of said stop- 115 per.

2. In a handle for bottle stoppers, the combination with a paper disk, of a handle comprising a piece of sheet metal having a portion adapted for a finger-grip, and having an 120 angular foot portion formed below the finger-grip adapted to bear upon the upper side of said disk, and having a pair of integral V-shaped points formed below said foot portion adapted to be driven through the disk and 125 clenched against the underside of said disk beneath said foot portion, for the purpose of rigidly attaching the handle to said disk.

3. In a device of the class described, the combination with a disk bottle stopper, of a 130

metallic handle comprising a portion adapted for a finger-grip having an angle-portion adjoining said finger-grip, and having a plurality of binding-points formed with said 5 angle-portion adapted to pierce said stopper and to be bent and clenched against the underside of said stopper opposite said angle-portion, the said finger-grip, when secured in place, being disposed at right-angles to said

angle-portion and also to the plane of said 10 disk.

In testimony whereof I affix my signature in presence of two witnesses.

DAVID B. SANFORD.
